SNOWSHOE

Frederick T. Paden, Collingswood, N. J.

Application January 10, 1950, Serial No. 7,105

Term of patent 7 years

(Cl. D34—14)

To all whom it may concern:

Be it known that I, Frederick T. Paden, a citizen of the United States of America and residing at Collingswood, New Jersey, have invented a new, original, and ornamental Design for a Snowshoe, of which the following is a specification, reference being had to the accompanying drawings, forming a part thereof.

Fig. 1 is a top plan view of a snowshoe, showing my new design; and

Fig. 2 is a side elevation of the same.

A bottom plan view would have practically the same appearance as Fig. 1.

I claim:

The ornamental design for a snowshoe, as shown and described.

FREDERICK T. PADEN.
